United States Patent Office.

RUSSEL WHEELER, OF UTICA, NEW YORK.

Design No. 2,847, dated December 10, 1867.

DESIGN FOR A COOK'S STOVE.

The Schedule referred to in these Letters Patent and making part of the same.

TO ALL WHOM IT MAY CONCERN:

Be it known that I, RUSSEL WHEELER, of the city of Utica, in the county of Oneida, and State of New York, have invented a new and improved Design for a Cook-Stove; and I do hereby declare that the following is a full and exact description thereof, reference being had to the accompanying drawings.

The nature of my invention consists in a new design for a cook-stove, as represented in the accompanying drawings.

To enable others skilled in the art to make and use my invention, I will proceed to describe its design and construction.

The stove is represented in Figure 1 on the accompanying drawings, and is of cast iron, and is designed for a cook-stove.

What I claim as my invention, and desire to secure by Letters Patent, is—

The general form and design of the stove, as represented in fig. 1 of the accompanying drawings.
